UNITED STATES PATENT OFFICE.

JOHN C. BARBER, OF CHICAGO, ILLINOIS.

SIDE BEARING FOR CARS.

No. 873,404.

Specification of Letters Patent.

Patented Dec. 10, 1907.

Application filed June 3, 1907. Serial No. 377,059.

To all whom it may concern:

Be it known that I, JOHN C. BARBER, a citizen of the United States, residing at Chicago, in the county of Cook and State of Illinois, have invented certain new and useful Improvements in Side Bearings for Cars; and I do hereby declare the following to be a full, clear, and exact description of the invention, such as will enable others skilled in the art to 10 which it appertains to make and use the same.

My present invention relates to side bearings for cars and has for its object to improve the same in the several particulars herein- 15 after noted.

The invention consists of the novel devices and combinations of devices hereinafter described and defined in the claims.

In practice it has been found that high, 20 cars should have less side bearing clearance than low cars. Also the amount of side bearing clearance which is desirable depends somewhat on the distance that the side bearing is located from the center bearing, and 25 this varies in different cars. Also, in different cars of the same type, the distance between the truck bolster or side bearing support of the truck and the overlying body bolster of the car will vary. Furthermore, 30 under rough service and continued use, there is a tendency for the truck bolster and the overlying car body bolster to work closer together. All of these conditions make desirable a vertically adjustable side bearing. 35 Hence, as the principal feature of my present invention, I provide a novel construction whereby the side bearing is made vertically adjustable.

In the accompanying drawings which 40 illustrate the invention, like characters indicate like parts throughout the several views.

Referring to the drawings, Figure 1 is a plan view of one of the improved side bearings. Fig. 2 is a bottom plan view of the 45 same. Fig. 3 is a vertical section taken on the line $x^3 x^3$ of Fig. 1; and Fig. 4 is a side elevation of the improved side bearing, showing also portions of a truck bolster and a car body bolster between the ends of which the 50 side bearings are applied.

The improved side bearing, in its preferred form, comprises three rollers 1, a divided or two-part roller supporting bracket 2 in which the trunnions of said rollers are journaled, a 55 base member 3, which, as shown, is bolted or

otherwise rigidly secured to the underlying end of the truck bolster 4, and an intermediate adjusting member 5 by means of which the roller bearing bracket 2 may be vertically adjusted. 60

The intermediate adjusting member 5 is in the form of a sleeve and it is provided with internal threads that engage external threads on an upwardly extended sleeve or hub portion 3^a of the base member 3. The roller bearing bracket 2 is provided with projecting flanges 2^a that rest directly upon the upper portion of the intermediate member or adjusting sleeve 5, and the two parts thereof are divided on a line that extends transversely of the intermediate portions of the rollers 1, so that the seats for the trunnions of the said rollers are adapted to be moved apart and toward each other for the purpose of removal or application to said trunnions. 75 Preferably, the two sections of the said bearing bracket 2 are rigidly secured together by rivets 6 passed through depending flanges 2^b of said bracket, and the said flanges 2^b at their ends are bifurcated or notched so that 80 they engage vertical ribs or guide lugs 7 formed on the interior of the hub 3^a. In this way, the roller bearing member 2 while free for vertical adjustments under the action of the adjusting sleeve 5, is held against rotation and, hence, the rollers 1 are always held in proper working positions for engagement with the roller bearing plate 8 of the car body bolster 9. 85

In Fig. 3, the roller bearing bracket 2 is shown in its lowermost position, in which position its flange 2^a bears against the top of the hub 3^a as well as against the top of the adjusting sleeve 5. 90

In Fig. 4, the adjusting sleeve 5 is shown 95 as screwed upward on the hub 3^a so as to move the bearing bracket 2 and its rollers 1 higher up than shown in Fig. 3, and in this adjustment of the parts the flange 2^a of said bracket 2 rests only upon the top of the said adjusting sleeve. Immediately underlying the flange 2^a of the bearing bracket 2, the adjusting sleeve 5 is provided with an outwardly extended flange 5^a. Both of these flanges 2^a and 5^a are provided with perforations that are adapted to be moved into registration in different rotary adjustments of the said sleeve 5 with respect to said bracket 2, and through which split keys 10 or other suitable lock devices are adapted to be passed 100 105 110

to lock the sleeve 5 against rotation and, hence, in any vertical adjustment in which it may be set.

What I claim is:

- 5 1. A vertically adjustable side bearing for cars comprising a base member, a vertically adjustable bearing bracket held against rotation in respect to said base member, rollers on said bracket, an intermediate rotary adjusting member operative on said base member and bearing bracket to vertically adjust said bracket and its rollers, and means for locking said adjusting member against rotation, substantially as described.
- 10 15 2. A vertically adjustable side bearing for cars, comprising a base member, a rotary adjusting member having threaded engagement with said base member, a bearing bracket supported by and vertically adjustable with 20 said adjusting member, but held against rotation with respect to said base member, and bearing rollers journaled in said bearing bracket, substantially as described.
- 25 3. A vertically adjustable side bearing for cars, comprising a base member having an externally threaded hub portion, an adjusting sleeve surrounding and having threaded engagement with said threaded hub, a roller
- bearing bracket supported by said sleeve but connected to the hub of said base member 30 with freedom for vertical movement but held thereby against rotary movement, and bearing rollers mounted on said bearing bracket, substantially as described.
4. In a side bearing for cars, the combination with a base member having an externally threaded hub 3^a and internal guide ribs 7, of an adjusting sleeve 5 working with threaded engagement on said hub, a two-part roller bearing bracket 2 having a projecting flange 40 2^a resting upon said sleeve 5 and having flanges 2^b, the ends of which embrace said guide lugs 7, thereby holding the said bracket 2 against rotation but permitting vertical movement thereof, bearing rollers mounted 45 on said bearing bracket, and means for locking said adjusting sleeve 5 against rotation with respect to said bearing bracket, substantially as described.

In testimony whereof I affix my signature 50 in presence of two witnesses.

JOHN C. BARBER.
